(57) **CLAIM**

The ornamental design for a motorcycle tire, as shown and described.

DESCRIPTION

FIG. 1 is a perspective view of a motorcycle tire showing our new design;

FIG. 2 is a front view thereof; the back view being a mirror image thereof;

FIG. 3 is a top view thereof; the bottom view being identical;

FIG. 4 is a right side view thereof;

FIG. 5 is a left side view thereof;

FIG. 6 is a fragmentary enlarged front view;

FIG. 7 is a cross-sectional view taken along line 7-7 in FIG. 6; and,

FIG. 8 is a cross-sectional view taken along line 8-8 in FIG. 6.

The broken lines showing portions of the motorcycle tire are for the purpose of illustrating environmental structure and form no part of the claimed design. The light stippled surface shading represents the surface of the tire tread, and the dark stippled surface shading represents the recessed portion of the tread grooves, having the depth as shown in FIGS. 7 and 8.
